Primary Examiner — Jennifer L Rempfer*Assistant Examiner* — Danielle Nichole Bowly(57) **CLAIM**

The ornamental design for a writing implement, as shown and described.

DESCRIPTION

FIG. 1 is a perspective view of a writing implement showing my new design;

FIG. 2 is a front view thereof;

FIG. 3 is a left side view thereof;

FIG. 4 is a right side view thereof;

FIG. 5 is a rear view thereof;

FIG. 6 is a top view thereof;

FIG. 7 is a bottom view thereof; and,

FIG. 8 is a left side view thereof, with the cap in an alternative position.

The broken lines are for illustrative purpose only and form no part the claimed design.

1 Claim, 3 Drawing Sheets(56)
